UNITED STATES PATENT OFFICE

135,740

DESIGN FOR A TOSSING RING

Benjamin D. Hodge, Houston, Tex.

Application March 11, 1943, Serial No. 109,724

Term of patent 14 years

To all whom it may concern:

Be it known that I, Benjamin D. Hodge, a citizen of the United States, residing at Houston, in the county of Harris and State of Texas, have invented a new, original, and ornamental Design for a Tossing Ring, of which the following is a specification, reference being had to the accompanying drawing, forming part thereof.

Figure 1 is a plan view of a tossing ring showing my new design.

Figure 2 is an edge elevational view thereof.

I claim:

The ornamental design for a tossing ring, as shown.

BENJAMIN D. HODGE.
